UNITED STATES PATENT OFFICE.

JOHN F. SAUERMAN, OF COAL HILL, ARKANSAS, ASSIGNOR OF ONE-HALF TO
EDWARD S. STIEWEL, OF SAME PLACE.

CHAIN PIPE-WRENCH.

SPECIFICATION forming part of Letters Patent No. 480,140, dated August 2, 1892.

Application filed February 23, 1892. Serial No. 422,440. (No model.)

To all whom it may concern:

Be it known that I, JOHN F. SAUERMAN, of the city of Coal Hill, county of Johnson, and State of Arkansas, have invented certain new and useful Improvements in Chain Pipe-Wrenches, of which the following is a full, clear, and exact description, reference being had to the accompanying drawings, forming a part hereof.

10 My invention relates to improvements in chain pipe-wrenches; and it consists in the novel arrangement and combination of parts, as will be more fully hereinafter described, and designated in the claim.

15 In the drawings, Figure 1 is a front elevation of my complete invention, showing the same applied to a pipe and in position to turn the same. Fig. 2 is a perspective view of the jaw forming a part of my invention. Fig. 3 20 is a detail view in plan showing the upper end of the lever, and Fig. 4 is a top plan view showing that end of the jaw for receiving the free end of the chain.

The object of my invention is to greatly 25 improve the chain wrenches heretofore constructed; and it consists, essentially, of three elements—namely, a lever, chain, and movable jaw—which when the parts are united, as hereinafter described, the pipe to which the 30 said invention is applied is gripped by the manipulation of the lever in the proper direction and will release its grip upon said pipe when the said lever is moved in the opposite direction.

35 My invention is especially constructed to overcome all objections that other wrenches of the same type possess, the most important objection being disfiguring the said pipe in many ways by the employment of a bar which 40 is brought in contact with the surface of the pipe.

Referring to the drawings, 1 represents a lever, which is tapering in longitudinal dimensions and rectangular in cross-section, the 45 dimensions, however, being only a matter of convenience. The upper end 2 of the lever 1 is suitably shaped and provided with a circular opening 3, which provides means for attaching the movable jaw, as hereinafter 50 described.

To one side of the lever 1, at the upper end of the same, is formed an extension 4, which is also provided with a circular opening 5, said opening being of smaller dimensions than the opening 3 before referred to.

55 6 represents a chain constructed of flat links and which may be of any suitable length, one end of which is movably attached to the extension 4 of the lever by means of a bolt or rivet 7 passing through an enlargement 8, 60 formed on said end of the chain, and through the opening 5, formed in said extension, by means of which the chain is free to move. The gripping-jaw which I employ may be formed by forging the same or made in parts, 65 as illustrated in the drawings, the construction of which I shall now proceed to describe.

9 represents the gripping-jaw, which consists of two plates 10, shaped and formed in the manner as hereinafter described.

70 Referring to Fig. 1 as a better illustration, 11 represents the rounded enlarged portions of the said plate and said portions provided with suitable openings 12, through which a bolt or rivet 13 is adapted to be passed, promising, however, that said bolt also passes through the opening 3, formed in the upper end of the lever 1, forming a movable connection between said jaw and lever. That surface of the plates 10 which comes in contact 75 with the outer surface of the pipe to be turned are provided with teeth 14, which are so formed as to slide upon the pipe in one direction, but grip the said pipe when the jaw is moved in the opposite direction. Leading from the said 80 enlarged portions 11 of the said plates 10 are angular-shaped extensions 15, the inner surfaces of the horizontal portions of the said plates shaped in a manner hereinafter described.

90 16 represents a bolt or rivet which passes through the said plates 10 for holding the same a proper distance apart, and, further, by the use of the said bolt the said plates are made rigid with one another.

95 In Fig. 4 I have shown more clearly the construction of the horizontal portions 15 of the plates 10, showing in addition to said construction the location of the chain between said plates and the manner of securing the 100

said chain within and between the said plates. Looking from the end of the said horizontal portions 15 of the said plates, 17 represent cut-away portions formed on the inner surfaces of the said plates, leaving two projections 18, between which projections one of the links of the chain 6 is adapted to be inserted and the adjacent links located within the spaces formed by the said cut-away portion 17.

By the construction of the plates as above described the chain is held rigidly by said jaw, which is absolutely necessary in order that the gripping will take a firm hold upon the pipe to be turned and when the lever 1 is moved in the proper direction for turning said pipe.

In Fig. 1 is shown the wrench above described in its proper position upon a pipe, which when the lever 1 is moved toward the right looking at said figure the gripping-jaw 9, or more properly the tooth portion of the same, will be brought in contact with the surface of the pipe to be turned, the resistance of the lever 1 being at that point where the chain 6 unites with the said lever, and the resistance of the jaw 9 being also upon the chain 6, causing not only the said gripping portion of the jaw to come in contact with the pipe, but also the chain 6, which also, in addition to the said jaw, acts to grip the pipe. When the lever 1 is moved in the opposite di-

rection to that above described, the jaw would be moved from the pipe, there being no resistance, and the entire wrench allowed to be moved freely about the pipe.

The wrench above described is not only simple in construction, but very effective in its results and can be used under all circumstances, either upon small or large pipes, with like results.

Having fully described my invention, what I claim is—

A chain pipe-wrench consisting of a lever 1, an extension 4, formed on one side of the same, a chain one end of which is movably attached to the said extension, a jaw 9, adapted to be movably attached to the said lever and composed of plates 10, teeth 14, formed on the impinging surfaces of said plates, angular extensions 15, formed by the said plates, a bolt 16 for rigidly attaching the said plates together, cut-away portions 17, formed on the inner surfaces and at the ends of the said plates, leaving projections 18, and a bolt or rivet 13 for attaching said jaw to the said lever, substantially as described.

In testimony whereof I affix my signature in presence of two witnesses.

JOHN F. SAUERMAN.
